DESIGN FOR A SANDGLASS TIMER

Jacob M. Weiss, Brooklyn, N. Y.

Application April 4, 1940, Serial No. 91,473

Term of patent 7 years

To all whom it may concern:

Be it known that I, Jacob M. Weiss, a citizen of the United States, residing at 1558—54th Street, in the Borough of Brooklyn, county of Kings, city and State of New York, have invented a new, original, and ornamental Design for a Sandglass Timer, of which the following is a specification, reference being had to the accompanying drawing, forming part thereof.

The figure is a perspective view of a sandglass timer, showing my new design.

I claim:

The ornamental design for a sandglass timer, substantially as shown.

JACOB M. WEISS.
